UNITED STATES PATENT OFFICE.

WILLIAM J. LANKFORD AND WALTER H. CHAPPELL, OF CHANUTE, KANSAS.

CONCRETE RAILWAY-TIE.

1,384,326.

Specification of Letters Patent. Patented July 12, 1921.

Application filed October 30, 1920. Serial No. 420,605.

To all whom it may concern:

Be it known that we, WILLIAM J. LANKFORD and WALTER H. CHAPPELL, citizens of the United States, residing at Chanute, in the county of Neosho and State of Kansas, have invented a new and Improved Concrete Railway-Tie, of which the following is a specification.

This invention has reference to improvements in railway ties, particularly concrete ties and primarily our said invention has for its purpose to provide an improved construction of railway tie of the general character stated composed of a plurality of sections in endwise alignment and adapted for being readily connected or assembled to the operative condition and for coöperative connection with means for readily attaching the parts and for disconnecting them in such manner whereby removal and renewal of the said parts may be expeditiously and conveniently accomplished.

Another and essential feature of our invention is to provide a concrete railway tie of a practical and relatively economical construction, in which the rail clamping and bracing elements are combined and connected for holding the rails down under the desired rigidity against spreading, and in such manner that lateral strains on the rail, particularly on curves, are so taken care of that danger of the rails creeping sidewise along the tie surface is reduced to the minimum, the several parts that constitute our improved construction of cement tie being also so designed whereby the end to end sections of the tie body are so joined that a sufficient flexibility or an elastic yielding of the parts is provided for so that when relieved of the car's weight, the said parts will relax to admit of the normal contraction and expansion of the rails and keep them from creeping or sliding on the tie and the strain and wear on the said tie materially overcome.

With other objects in view that will be hereinafter generally referred to, our invention embodies certain features of construction and novel arrangement of parts, all of which will be fully explained in the following detailed description, specifically pointed out in the appended claims and illustrated in the accompanying drawing, in which:

Figure 1 is a top plan view of our con-

crete tie and illustrates a preferred construction thereof.

Fig. 2 is a side elevation of our tie.

Fig. 3 is a longitudinal section of one end of the tie, portions of the rail clamping and longitudinal connecting members being shown in elevation.

Figs. 4, 5 and 6 are detail views of portions of the rail clamping means herein-after specifically referred to.

Fig. 7 is a diagrammatic plan view of one end of the tie and portions of the rail clamping devices.

Fig. 8 is a detail longitudinal section of the key bolt, the tie plate and a portion of the longitudinal connecting bar.

Fig. 9 is a detail perspective view of one end of said connecting bar.

Figs. 10 and 11 are respectively a plan view and an edge view of the tie plate.

Fig. 12 is an elevation view of the hook or connecting device for joining the adjacent ends of the longitudinal connecting or rail clamping rods.

Fig. 13 is a diagrammatic side elevation of a further modification of our invention hereinafter specifically explained.

In the drawings in which like numerals designate like parts in all of the figures and referring more particularly to Figs. 1 and 2, the body portion of the tie consists of two like half sections 1—1, which sections are disposed end to end and in longitudinal alignment and, in the practical development of our concrete tie, the outer end of each section has a clover leaf or three lobe shape, as shown in Fig. 1, the opposite sides and the end faces being vertical and formed with panels or recesses 2—2, the latter providing for a tight embedding of the tie in the ground, when placed in position for use and for convenient handling of the body sections 1—1, when placing the same in operative position or removing them, when necessary.

Each of the tie sections 1 has a countersunk recess 3 at the inner end and the said recesses, when the tie sections are adjacently positioned, form a space into which is received a cushioning block 4, the purpose of which is to take up and intercept vibrations of the tie body, such formation of the adjacent ends of the tie sections also avoiding the effect of rigidity of the tie.

The rails 10—10, in my construction of concrete rail tie, do not rest directly on the

tie top but engage metal plates 5 that are hereinafter termed tie plates, the application of which and the means for holding them secure upon the top of the tie sections 1 and 5 the clamping devices that coöperate therewith and the rails being best shown in Fig. 3.

By referring now to the aforesaid Fig. 3 and Figs. 10 and 8, it will be noticed that 10 the plate 5, at its outer edge, has a central recess 50 and, at the opposite edge, it has a centrally disposed aperture 51, the purpose of which will presently appear, it also having apertures 6—6 at the opposite ends in 15 each of which is received a combined clasp and bolt 7, the latter serving as spikes for clasping over the adjacent rail flange of the rails.

The bolts 7 have angled portions 70 at the 20 lower end for coengaging with reinforcement plates 8 that extend across and under the main or draw bars 9 whose outer ends terminate in upward and backward turned hooks 90 for fitting over the outer rail flange 25 and for opposing the bolts 7, as is clearly shown in the drawings.

Cushion members in the nature of elongated plates 11 seat under the tie plates 5 and their inner opposite edges are secured 30 by the clasp or hook 7.

The outer edges of the plates 11 are notched and straddle the hook ends of the draw bars 9.

12—12 designate keepers that are embedded in the cement sections 1 and each of the said keepers has an inturned hook 12^a that fits over the outer edges of the tie plates 5 at each side of the opposite ends of the draw bars 9 and in addition to holding down 40 the tie plates the said keepers avoid spalling of the concrete at the outer edges of the said tie plates.

The body sections 1—1 each have a channel or groove that extends lengthwise therefrom near the outer ends to and through the inner end and at the said inner end, the grooves 16—16 terminate in depressions or enlargements that form a sufficient space or seat for receiving and for the free adjustment of a turn buckle 17 (or other like coupling device) that joins the inner adjacent threaded ends of the draw bars 9—9 whose outer hook-shaped ends engage the outer flanges of the rail, it being understood that, 55 by proper adjustment of the turn buckle 17, the bars 9 may be drawn together or relaxed for holding the opposite rails, for the proper setting thereof.

To further hold the rails against spreading or outwardly creeping, brace members 19 are provided and they are held in engagement with the outer face of the rail webs, the innermost end of the said brace contacting the under side of the head or tread portion of the rail and for effecting a strong

and durable connection for the brace, whereby to adapt it for taking up the lateral outward stress on the rail, the said braces include base portions 19^a that seat in the outermost end of the longitudinal channels or 70 grooves 16 and abut the outermost edges of the hook ends of the draw rods 9—9, as best shown in Fig. 3, by reference to which it will be observed each brace portion 19^a includes an outwardly extended clutch member 75 19^b, which members are apertured for readily fitting over the projected threaded ends of the bolts 20 embedded in the concrete body and which receive clamp nuts 21 that secure the brace ends 19^a down onto the 80 tie body.

22—22 designate ordinary headed bar members and they are embedded in the tie body, when pouring the cement into the desired tie body and the said bar members 85 have their ends projected laterally at the opposite sides of the meeting ends of the body sections 1—1 and 23—23 denote hook members that extend across the gap between the ends of the body sections 1—1 and hook over 90 the heads of the members or bars as is clearly shown in Figs. 1 and 2.

Instead of shaping the ends of the connecting devices 23—23 as shown in Figs. 1 and 2, the said devices may be formed as 95 shown in Fig. 12, by reference to which it will be noticed the angled ends of the connecting bar have bayonet slots 23^a for slipping over the heads of the bars 22 and interlockably sliding along the shanks of the 100 said angled ends.

Referring now more particularly to Figs. 3, 4, 5 and 6 of the drawings, it will be noticed that the spike or clasp bolts 7 are 105 rotatively mounted with respect to the rail base so that they may be readily turned to one side in a plane parallel with and outside of the said rail base, as is clearly indicated in the detail view, Fig. 5, it being understood that, when the members 7 are positioned as in Fig. 5, the rail may be readily lifted out of the operative position along the tie, it being also apparent that when the members 7—7 are turned at right angles to the rail base and extended over the said 110 base, by tightening up the draw bars 9—9, a rigid connection for holding the rail upon the tie is provided for.

To secure the clasps or bolts 7—7 in their clamping position, key plates 24 are provided that are held down between the adjacent sides of a pair of spikes or bolts by key bolts 25 that pass down through the key plates 24 and which are held between the adjacent pairs of spikes or clamp members 120 7—7, when the latter are projected over the base flange of the rail and the said plates 24 are secured, as before stated, by the key bolts 25, which pass down through the centrally disposed apertures 51 in the plates 5, 130

through elongated slots 95 in the draw bar members 9 and also through cushion plates that engage the under side of the draw bar 9 and with which the angled portions 70 on 5 the lower end of the bolts or clasps 7 engage, when such bolts are adjusted to the rail base clamping position, as is clearly indicated in Figs. 1, 2, 3 and 6.

In Fig. 7 is shown the means for clamping the rail onto the tie and, in this form 10 of my invention, the same general arrangement of parts appears as in Figs. 1, 2 and 3, the differentiating feature being that in addition to the draw bar hook connections 15 for the outer base flange of the rail, a pair of rotatable spikes or clamp members 27-27 are provided, whose lower ends pass through cushion plates 28, which extend diagonally under the rail and have their 20 inner ends apertured for passing the lower ends of the inner bolts or clasps 7-7, as indicated in dotted lines in the said Fig. 7.

Another modification of our concrete tie 25 construction is indicated in Fig. 13. In this form, the spikes that clasp the inner base flange of the rail are shown as embedded in the tie body and the outer flange of the rail held down by clamp plates 35, and nuts 36 which engage the upper threaded end 37 of 30 fixed rods embedded in the cement body and whose upper threaded ends are so disposed with reference to the rail base flange that the plates 35 and the nuts 36 may be conveniently applied.

35 In the several forms of our concrete tie structure hereinbefore described and illustrated in the drawings, the outer ends of the body sections of the tie have projected headed studs 60 that are provided for engaging with slotted ways 61 in vertical adjustable wings or shields 62 that are provided to prevent wastage of the filling while tamping at the ends of the tie, particularly when the tie ends are concaved on their under side as indicated by dotted line A on 40 Fig. 3.

In the practical assemblage of the parts 50 that constitute our improved construction of concrete tie, the rail receiving ends are reinforced by longitudinally extended metal bars or plates 75 and like transversely placed bars or plates 76 shaped as shown in dotted lines of Figs. 3 and 7 and which extend down into the tie body where they pass under the part of the tie where the rail crosses as indicated in Fig. 7, such placing of the 55 reinforcing members 75 causing the weight that comes onto the tie to tend to draw endwise on the reinforcement.

60 While the specific arrangement of the parts shown and described illustrate one practical presentation of our invention we do not limit ourselves to such specific details of construction since in the practical 65 development of our improved concrete tie

the special arrangement of parts may be modified or varied as conditions of our application of our improved tie may make necessary, without departing from our invention as comes within the scope of the appended claims.

70 What we claim is:

1. In a concrete railway tie, two body sections, means for holding said sections in endwise relation, the said means including a 75 longitudinal connecting bar having at the opposite ends clamping members for engaging the outer flanges of the rail bases mounted thereon, and other means embedded in each body section for clamping the inner 80 flanges of the rails mounted thereon.

2. In a concrete railway tie, two body sections, means for holding said sections in endwise relation, the said means including a longitudinal connection bar having at the opposite ends clamping members for engaging the outer flanges of the rail bases mounted thereon, and other means embedded in each body section for clamping the inner 85 flanges of the rails mounted thereon, said connection bar consisting of two sections and adjustable coupling means connecting the said two sections.

90 3. In a concrete railway tie of the character described, the combination of a body composed of two sections, means for holding said sections in endwise relation, clamp members embedded in each of the said sections for engaging the inner and outer flanges of the rails on the respective outer 95 ends of the said sections and a brace member secured on the outer end of each body section that engages the outer face of the web 100 of an adjacent rail.

105 4. In a concrete tie of the character described, the combination with a pair of concrete body sections, means for holding the said sections in endwise relation, the said means including a member embedded in each of the adjacent ends of the said sections 110 and coupling members that span the meeting ends of the said adjacent body sections at each side thereof and which interlockably engage the aforesaid members embedded in the said adjacent ends of the body sections.

115 5. In a concrete railway tie, the combination with the tie body having means at each end for engaging and clamping the rails thereon; of a shield member mounted on each end of the said tie, the said members 120 being vertically adjustable with respect to the said tie body ends for the purposes specified.

125 6. In a concrete railway tie, a concrete tie body composed of two sections, means for holding the said sections in endwise relation, means embedded in each body section for engaging and clamping the inner flanges of the rails held thereon and a member that extends lengthwise of the two body sections,

the said member being provided with a clamp hook at each end for hooking over and onto the outer base flange of the rails at the ends of the tie body.

- 5 7. In a concrete railway tie, a concrete tie body composed of two sections, means 35 for holding the said sections in endwise relation, means embedded in each body section for engaging and clamping the inner 40 flanges of the rails held thereon and a member 45 that extends lengthwise of the two body sections, the said member being provided with a clamp hook at each end for hooking over and onto the outer base flange of the rails at the ends of the tie body, said member including means whereby to extend or retract the length thereof.

8. A concrete tie composed of a pair of concrete body sections having panels in the 20 opposite side faces thereof, concavities in the bottom thereof, a shield on the outer end of each section, said shields being vertically adjustable whereby to project them below the bottom of the tie and devices secured 25 to the tie body section for clamping the rails at their respective ends onto the tie and against spreading.

9. In a concrete railway tie, a pair of opposing body sections, means for securing 30 the said sections end to end, other means mounted upon and lengthwise adjustable for engaging and clamping the outer base

flanges of a rail, further means for engaging the inner base flange of the rail, the said further means including bolts having portions at the upper end for clasping the said inner rail base, the said bolts being rotatably mounted with respect to and adjacent the rail base, whereby they may be turned back out of engagement with the said rail 40 base, and devices for holding the bolts against rotation, when they are turned onto the rail base to constitute rail securing means opposing the means that secure the outer rail base flange. 45

10. In a cement tie construction of the character described, the combination with the tie body and a rail member, the said tie body having a longitudinal groove that extends beyond the rail receiving point, a tie 50 plate that bridges said groove and upon which the said rail rests, means for clamping the inner edge of the tie plate and the corresponding base flange of the rail in operative connection with the tie body, other 55 means engaging the outer edge of the tie plate for holding the said plate onto the tie body and a draw bar that seats in the longitudinal groove of the tie body and has a hook portion engaging the outer base flange 60 of the rail.

WILLIAM J. LANKFORD.
WALTER H. CHAPPELL.
